DRAFT AND BUFFER GEAR

John H. Link, Merion Station, Pa., assignor to
W. H. Miner, Inc., Chicago, Ill., a corporation
of Delaware

Application June 28, 1933, Serial No. 677,965

7 Claims. (Cl. 213—9)

This invention relates to improvements in draft and buffer gears especially adapted for use in connection with mine cars.

One object of the invention is to provide a combined draft and buffer gear for cars, wherein both the draft and buffering shocks are cushioned by the same shock absorbing means.

Another object of the invention is to provide in a gear of the character indicated, including shock absorbing means, mechanism for compressing the shock absorbing means inwardly toward the end of the car in both buff and draft.

A more specific object of the invention is to provide a combined draft and buffer gear for mine cars, including buffer heads at opposite sides of the end of the car, shock absorbing spring means at opposite sides of the car yieldingly resisting inward movement of the buffer heads, and a draft member centrally of the end of the car, wherein means is provided for transmitting the draft movement from the draft member to the buffer heads and effecting movement of the buffer heads in a direction reverse to the movement of the draft member to compress the shock absorbing spring means inwardly toward the end of the car.

Other objects of the invention will more clearly appear from the description and claims herein-after following.

In the drawing, forming a part of this specification, Figure 1 is a horizontal sectional view, partly broken away, of one end portion of a mine car, illustrating my improvements in connection therewith, the section corresponding substantially to the line 1—1 of Figure 2. And Figure 2 is a front elevational view of the structure shown in Figure 1.

In said drawing, 10 designates the end portion of a mine car, to which my improved combined draft and buffer gear is attached. My improvements comprise broadly a housing A; a pair of buffering heads B—B; a draft member C; a pair of levers D—D; and two sets of springs E—E and E—E.

The housing A comprises a vertical end wall 11, spaced side walls 12—12, and top and bottom walls 13 and 14. The side walls 12—12 and the top and bottom walls 13 and 14 are preferably formed integral with the wall 11 and project outwardly therefrom. The wall 11 may form an integral part of the end sill of the car, which end sill may also form an integral part of the under-frame structure of the car, or may comprise a separate member secured to said underframe structure. The top and bottom walls 13 and 14

of the housing A are cut away at the center to accommodate the usual coupling link, which is connected to the draft member C. The side walls 12—12 have inwardly turned, relatively thick flanges 15—15 at their forward ends, which form front stops for the buffering heads B—B. At each side of the housing A inwardly of the corresponding wall 12, the wall 11 is provided with a forwardly projecting, relatively short, vertical wall 16, which cooperates with the corresponding buffering head B, as hereinafter pointed out, so as to limit inward movement of the head. Between the wall 16 at each side of the housing A and the corresponding side wall 12, the top and bottom walls are provided with ribs 17—17, which have their front surfaces in alignment with the end face of the wall 16 so as to be engaged by the inner end of the buffering head B when the latter is stopped in its movement by the wall 16.

The buffering heads B—B, which are disposed at opposite sides of the gear, are of like design, each being in the form of a cap having a front wall 18 provided with a rounded outer buffering surface. At the inner end, each head B is provided with laterally outwardly projecting stop flanges 19—19. The stop flange 19 at the outer side of the buffering head B has shouldered engagement with the flange 15 at the corresponding side of the housing A to limit outward movement of the head B.

The draft member C is arranged between the buffering heads B—B and has laterally projecting arms 20—20 at opposite sides thereof, which cooperate with the levers D—D, as hereinafter pointed out. The central portion of the draft member C is enlarged, as clearly shown in Figure 1, and has a vertical opening 21 therethrough adapted to receive the usual coupling pin which connects the draft member to the coupling link. Each arm 20 of the draft member C has a forwardly projecting, angular extension 22 at the extremity thereof. The enlarged portion of the draft member C has a flat rear surface 23, which normally bears on the wall 11 of the housing A. At opposite sides of the draft member C, the top and bottom walls 13 and 14 of the housing A are preferably provided with guide ribs 24—24, which cooperate with the ends of the arms 20—20.

The levers D—D, which are disposed at opposite sides of the draft member C, are of like design, each having an enlarged central portion 25 and oppositely projecting inner and outer arms 26 and 27. The outer arm 27 engages the inner flange 19 of the corresponding buffering head B, as clearly shown in Figure 1. The inner arm 26 is

offset rearwardly and has a hooked end 28, which engages over the projection 22 on the arm 20 at the corresponding side of the draft member C. Each lever D is pivotally supported on the housing A by means of a bolt 29 extending through the enlarged central portion of the lever and top and bottom walls 13 and 14 of the housing A. As shown in Figure 2, the top and bottom walls 13 and 14 are preferably thickened to reinforce the same at the points where the bolt 29 is secured.

10 The two sets of springs E—E and E—E are arranged at opposite sides of the housing A, each set comprising two coils having their opposite ends bearing respectively on the wall 11 of the housing A and the inner side of the front wall 18 of the corresponding buffering head B.

15 The operation of my improved combined draft and buffering gear is as follows: When a pulling force is applied to the draft member C, the same is moved outwardly away from the end of the car, thereby rocking the levers D—D on their pivots and forcing the buffering heads B—B inwardly against the springs E—E and E—E. As will be evident, during this action the buffering heads B—B are rocked on the flanges 15—15 of the side walls 20 12—12 of the housing A.

25 During a buffering action, the buffering heads B—B, which are engaged by similar buffering heads of an adjacent car, are forced inwardly toward the end of the car, compressing the springs E—E and E—E directly against the wall 11 of the housing A. Inward movement of the buffering heads B—B is limited by engagement of the inner ends of the same with the walls 16—16 and the ribs 30 17—17 and 17—17 of the housing A, thereby restricting the movement in both buff and draft.

35 I have herein shown and described what I now consider the preferred manner of carrying out my invention, but the same is merely illustrative and I contemplate all changes and modifications 40 that come within the scope of the claims appended hereto.

I claim:

45 1. In a combined draft and buffering gear for cars, the combination with fixed abutment means on the end of the car; of a supporting member; a pulling member movable on said supporting member; buffering heads at opposite sides of the pulling member, said heads being slidable inwardly on the supporting member; cushioning means interposed between each head and the abutment means and opposing inward movement of said head; and lever means swingable about fixed pivot means on said supporting member at 50 opposite sides of the pulling member for transmitting the draft force from the pulling member to the buffering heads respectively for forcing said heads inwardly toward said fixed abutment means.

55 2. In a combined draft and buffering gear for cars, the combination with fixed abutment means on the end of the car; of a supporting member; a buffer head movable inwardly on the supporting member; cushioning means interposed between said head and abutment means opposing inward movement of the buffer head; a pulling member movable outwardly away from the end of the car in draft, said pulling member being slidably guided on said supporting member; and lever means for transmitting movement from the pulling member to said buffer head to force the head inwardly toward the end of the car when the pulling member is moved outwardly, said lever means being swingable about a fixed pivot on 60 the car.

3. In a combined draft and buffering gear for cars, the combination with fixed abutment means on the end of the car; of a supporting member; a buffer head movable inwardly on the supporting member; cushioning means interposed between said head and abutment means opposing inward movement of the buffer head; a pulling member movable outwardly away from the end of the car in draft, said pulling member being slidably guided on said supporting member; and a lever pivoted between its ends on a fixed pivot on said supporting member and having one end engaging the pulling member and the other end engaging the buffer head for forcing the latter inwardly when the pulling member is moved outwardly away from the end of the car. 80 85 90

4. In a combined draft and buffering gear for cars, the combination with fixed abutment means on the end of the car; of a supporting member; laterally spaced buffer heads movable inwardly on the supporting member; cushioning means interposed between each head and the abutment means, said cushioning means opposing inward movement of the buffer heads, each buffer head having a laterally projecting flange on the inner side thereof; a pulling member movable outwardly away from the end of the car in draft, said pulling member being mounted on the supporting member at a point between said buffer heads, said pulling member having laterally projecting arms; and a pair of levers at opposite sides of the pulling member, each lever being pivoted between its ends on the supporting member, each lever having its opposite ends bearing respectively on the front side of the corresponding arm of the 100 105 110 pulling member and the flange of the corresponding buffer head.

5. In a combined draft and buffering gear for cars, the combination with fixed abutment means on the end of the car; of a supporting member; a pair of laterally separated buffer heads movable inwardly on the supporting member; cushioning means bearing on said abutment means and opposing inward movement of said buffer heads; a pulling member movable outwardly away from 115 the end of the car in draft, said pulling member being movably mounted on said supporting member between said buffer heads; and a pair of levers between said buffer heads and pulling member, each lever being fulcrumed between its 120 125 ends on the supporting member and having its opposite ends in rocking engagement with said pulling member and one of said buffer heads respectively.

6. In a combined draft and buffering gear for 130 cars, the combination with fixed abutment means at the end of the car; of a supporting structure at said end of the car; a draft member having oppositely extending, laterally projecting arms, said draft member being slidable outwardly on said 135 supporting structure; buffer heads at opposite sides of the draft member, said buffer heads being movable on said supporting structure, each buffer head having inner and outer laterally projecting flanges at opposite sides thereof, the 140 outer flange of each head having shouldered engagement with the supporting structure to limit outward movement of said head; cushioning means yieldingly bearing on said abutment means and opposing inward movement of the 145 buffer heads; and levers at opposite sides of the draft member operatively connecting the latter to the buffer heads, each lever being fulcrumed between its ends on said supporting structure and having its opposite ends in rocking 150

engagement respectively with the inner flange of one of said buffer heads and the arm at the corresponding side of the draft member.

7. In a combined draft and buffer gear for cars, the combination with a housing fixed to the end of the car, said housing having spaced side walls and a transverse rear wall, said side walls having inturned flanges at their outer ends; of a pair of laterally spaced levers pivoted between their ends on said housing, thereby providing inner and outer arms on said levers; a pair of buffer heads at opposite sides of said gear, each buffer head having laterally projecting

flanges at the inner and outer sides thereof, the outer flanges of said heads being engaged in back of the corresponding flanges of the housing and the inner flanges being engaged in back of the outer arms of the corresponding levers; shock absorbing springs having their opposite ends bearing on the rear wall of the housing and the inner sides of the buffer heads respectively; and a draft member movable outwardly of said housing, said draft member having laterally projecting arms at opposite sides engaging in back of the inner arms of said levers.
